CASH CARRIER APPARATUS.

No. 359,875.

Patented Mar. 22, 1887.

UNITED STATES PATENT OFFICE.

DAVID LIPPY, OF MANSFIELD, OHIO.

CASH-CARRIER APPARATUS.

SPECIFICATION forming part of Letters Patent No. 359,875, dated March 22, 1887.

Application filed March 15, 1886. Serial No. 195,336. (No model.)

To all whom it may concern:

Be it known that I, DAVID LIPPY, a citizen of the United States, residing at Mansfield, in the county of Richland, State of Ohio, have 5 invented certain new and useful Improvements in Cash-Carrier Apparatus, of which the following is a specification, reference being had therein to the accompanying drawings.

This invention relates to cash and parcel carriers for store-service, the object in view being to transmit cash and other articles from one station to another quickly and with the least possible noise, and also to provide suitable stations for receiving and sending the cars; 15 and the invention consists in certain features of construction, hereinafter described, and particularly pointed out in the claims.

Referring to the drawings, Figure 1 represents a car or carrier and a station, in side elevation, constructed in accordance with my invention. Fig. 2 is a plan view of the station, the car being in horizontal section. Fig. 3 is a vertical section of the depending support, illustrating the means of connecting the track 25 or cable therewith. Fig. 4 is a perspective of a series of stations, illustrating the means employed for adjusting and supporting the same. Fig. 5 is a plan view of the entire system. Figs. 6 and 7 are details, hereinafter described. 30 Fig. 8 is a central vertical section of the roller-supporting bracket.

Like letters indicate like parts in all the figures of the drawings.

Referring more particularly to Sheet 1 of the drawings, A represents a depending cylindrical hollow standard, which in this instance is secured to the ceiling of a compartment by means of an ordinary securing-plate, and is slotted and perforated, as at A', at a desired 35 point for the passage therethrough of the cable or track B, said slot or perforation registering with a perforation, A'', in a collar, A³, mounted upon said standard, which collar is provided with a set-screw, A⁴, passing through apertures formed in the collar and standard, and 40 adapted to bear upon a bifurcated clamp, A⁵, (see Fig. 3,) inclosed within the hollow standard, said clamp being adapted to grip the cable B. The ends of the cable are connected 45 with the walls of the compartment by suitable securing devices, between which and

the standard are arranged ordinary turn-buckles, C.

By the means just described it is apparent that the front end of the horizontal arm may 55 be adjusted to a desired position below the cable, for a purpose hereinafter specified, and that by loosening the clamp A⁵ any slack may be taken up by the turn-buckle C.

D represents a wedge-shaped arm into 60 which the bottom of the standard is swiveled, and which is secured in position by means of a set-screw, D². Extending from the rear end of the arm D to the standard A is a brace-rod, D', the object of which is to prevent horizontal 65 displacement of said arm when once adjusted with relation to the standard.

The brace-rods D' may be soldered or otherwise rigidly secured to the standard and arm D; or they may be adjustably secured, as are 70 the rods D⁴ and D^{2x}. (See Fig. 5.)

Extending from the arm D, at a point in line with the standard and to the wall of the compartment, is a guy-rod, D^{2x}, which passes through and is rigidly secured to a block, D³, 75 perforated for the passage and adapted to slide upon a second stay or rod, D⁴, extending from the extreme end of said arm. The object of this is to provide means for adjusting and maintaining the tapered or wedge-shaped arm 80 D in a direct line with the track or cable, the operation of adjusting being simply to loosen the binding-screw D⁵, adjust the rod in the desired direction, the stay D⁴ sliding within the block D³, and secure the arm in that position by 85 tightening the screw D⁵, thus preventing any lateral displacement; or, as shown at the right of Fig. 5, the block may slide upon the rod D⁴.

In Fig. 4 I have illustrated means for adjusting the arms D, where they are in a gang 90 or connected series, which is the case in the cash-room, each arm being for a cable or track leading to a different station of the store or compartment. For the purpose of preventing any vertical displacement, I connect each of 95 the hangers or standards in a gang or series by means of a connecting rod or stay, D⁶, and I may or may not, as desired, connect the arms D rigidly to the hangers or standards A. In order to provide for a lateral adjustment of 100 the arms D, I pass an adjusting-rod, D⁷, through apertures formed transversely in the arms,

and provide each of said arms with a binding-screw, D⁵, whereby a lateral adjustment is obtained, as indicated by dotted lines, Fig. 4, the standard, when rigidly secured to the arm 5 D, being adapted to rotate in the standard-plate secured to the ceiling.

Having described the means employed for supporting and adjusting the track, I will now proceed to describe the construction of the car 10 or carriage.

Referring more particularly to Figs. 1 and 2 of the drawings, E represents the platform or foundation, which is provided with or has formed thereon at each end a pair of vertical 15 ears or lugs, E', which are vertically slotted or bifurcated to form bearings E² for the axle E³ of the grooved rollers F. These axles are in fact screws provided with pointed or cone-shaped ends adapted to fit corresponding de- 20 pressions in the sides of the rollers F.

To tighten or loosen the rollers, it is only necessary to give the screws a turn in either direction, thus decreasing or increasing the tension on said rollers.

25 I have provided means for adjusting the carriage at a suitable distance below the track by reason of the bifurcations E² in the lugs E', in that it is plain that the rollers and axles may be raised or lowered in said bifurcations 30 and secured at a desired point therein by tightening the binding-screw E⁴, which binds the bifurcations of said lugs firmly against the axle of the bearings. The screw E⁴ may serve to compress the bearings against the 35 screw E³ to maintain it in a desired adjustment in relation to the grooved roller.

Now comes an important feature of my invention; and it consists in the manner of gradually and noiselessly stopping the car as it 40 reaches a station. Depending from the platform E of the car at the center, or it may be, as shown, at each end, and it may be formed as a part thereof, is a rectangular bracket, G, adapted to receive a pair of rollers, G', vertically supported therein, which are set at a distance apart slightly less than the largest portion of the arm D, which they are intended to embrace.

For a purpose hereinafter specified, I form 50 the rollers of rubber of medium elasticity.

The platform E is provided at each side and at its middle with laterally-projecting lugs or arms H, from which depend suitable hangers, H', secured to the lower ends of which is a flanged head, H², forming a receiver for the carrier proper, or receptacle H³, which is provided with diametrically-opposite bayonet-slots H⁴, adapted to receive a bar, H⁵, passing transversely through the interior of the receiver or flanged head H². By giving the cup or receptacle H³ an upward thrust into the flange of the head and a turn to the left it will, by the before-described means, be held in a locked position, and by reversing said operation the same may be withdrawn. (See Figs. 1 to 7.) By putting the rod H⁵ into the cup H², instead of in the cash-receptacle H³,

no unsightly bayonet-slots are exposed to view.

At each end of the platform E, and on top thereof, I mount a cushion or muffler, E⁶, between which and the grooved rollers the track or cable runs, its purpose being to prevent any noise occasioned by reason of the platform coming in contact with the cable when a sudden impetus is given the carriage.

It has been suggested that rubber rollers might be employed for movably supporting the carriage upon the wire, whereby the noise of the carriage when traveling along the wire would be obviated; but as said rollers sustain the weight of the carriage and its load they soon become worn, whereas my muffler does not necessarily press against the wire with sufficient force to materially injure the same, and yet it acts to deaden the noise.

It now becomes necessary to provide means for imparting motion to the carriage.

Referring more particularly to Figs. 1 and 6 of the drawings, I represents a roller which depends from the under surface of the arm D, near its rear end, said roller being similar to those mounted upon the car, the bearing I¹ being preferably the same, so as to overcome as much friction as possible. The forward 95 portion of the arm D is recessed, as at I², and provided with a pulley, I³.

K represents a movable block or starter, upon the top of which I mount a plate, K', which may be longitudinally apertured, as at K², for the purpose of working upon the track or cable B, which may pass through the same. (See Fig. 6.) Connected to the front portion of the starter K is a rope, cord, or chain, L, which passes forward along the top of the arm D, as shown by the arrows, over the pulley I³, and rearward under the arm and over the pulley or roller I, extending down a convenient distance, where it is provided with an operating-handle, L'. It will now be seen that, taking the car in the position shown in Fig. 1—ready for starting—a sudden jerk upon the handle L' will draw upon the cord L and starter K, which in turn forces the car from its position with an impetus sufficient to cause it to travel to the opposite station. Although the motion imparted is sudden, still, by reason of the cord L passing over the pulley I³, the starter will traverse nearly the entire length of the arm, thus imparting a pushing steady motion, the impetus being sufficient to carry the car to the opposite station. I prefer to form the starter K of rubber, or at least that portion thereof that comes in contact with the end of the car, in order to deaden the noise.

Now, for the purpose of insuring a steadiness of the starter K, I may provide the arm D upon its top with a longitudinal groove—in this instance a dovetail-groove, K³—and so form the bottom of the starter that it will conform to and freely slide within the same, as shown in Fig. 6.

Instead of passing the track or cable through the aperture K² of the plate K' of the starter,

I may simply slot the plate longitudinally, as at K², on the right of Fig. 5, and in this manner the cable will form a top guide, and thus the starter will be guided by the cable and permit of vertical adjustment of the front end of the arm independently of the cable.

As previously stated, the arm D is tapered or wedge-shaped, the taper beginning at about the point where the standard A is connected with said arm. The object of this arm is to form a station for receiving and gradually stopping the carriage after it has been sent from an opposite station. The distance apart of the rollers G' is slightly less than the widest portion of the tapered arm D, and, as before stated, they are made of rubber. Now, when a car traversing from one station to another reaches a point on the cable where the gradually-enlarged arm D is sufficient to come in contact with the rollers G', said car will be caused to gradually stop, the elasticity of the rollers G' being sufficient to cause a gradual even stoppage with little or no jar, and the car will be thus wedged in position, as shown in Fig. 2. The cash-receptacle can now be opened and its contents removed, and the carrier is now ready to transmit cash or other articles to the opposite station, where the gradual insertion of the wedge-shaped arm D between the rubber rollers at the opposite end of the car will cause a gradual and at the same time noiseless stoppage of the car at that point.

It will be seen that the device as a whole is exceedingly simple in operation and noiseless, thus doing away with the disagreeable constant clatter usually occasioned; and by reason of the anti-friction rollers a minimum force will be sufficient to cause its traversing the entire route.

The advantages of adjustability of all parts will also be readily seen, in that the carriage may be raised or lowered a sufficient distance from the arm D by means of its adjustable rollers, and that the arm D may be adjusted either laterally or vertically to insure its entrance exactly between the roller G', in order that an even pressure may be secured in stopping the carriage, and by reason of this gradual noiseless stoppage no rebound whatever is occasioned.

It is also apparent, by referring to Fig. 5, that the impetus of the carriage will be sufficient to carry the starter K of the receiving station back to its proper position, so that all that is necessary to be done is to give the handle L' a pull, and the carriage, with its cash or other article, will be quickly and noiselessly transferred over the cable B to the opposite station. By making the arm or station wedge-shaped horizontally the stoppage of the carriage thereby does not tend to throw parcels upwardly and out of any open receptacle, as would be the case were the arm wedge-shaped vertically; and, furthermore, there is less strain on the cable when stopping a swift-running and heavily-laden car.

Having thus fully described my invention and its operation, what I claim is—

1. In a cash-carrier, the combination of a horizontally wedge-shaped station, a cable, and a carriage adapted to embrace the sides of the station, substantially as specified. 70

2. In a cash-carrier, the combination of a horizontally wedge-shaped station, a cable, and a carriage provided with elastic devices arranged to embrace the station, substantially as specified. 75

3. In a cash-carrier, the combination of an adjustably-supported horizontally wedge-shaped station, a cable, a carriage mounted thereon and provided with station-embracing devices, and adjusting devices for regulating the relative position of the station with the cable and carriage, substantially as specified. 80

4. In a cash-carrier, a supporting-standard having a horizontally wedge-shaped adjustable arm mounted thereon, and devices for laterally and vertically adjusting said arm, substantially as specified. 85

5. In a cash-carrier, a station comprising a standard, a horizontally wedge-shaped arm adjustably secured thereto, and adjustable guys, whereby said arm may be laterally adjusted, substantially as specified. 90

6. In a cash-carrier, the combination of a supporting-standard provided with a receiving-arm, with a carriage adapted to be received by said arm, and a starter provided with a cord or chain extending under said carriage and over and under said arm, whereby a pull upon the same will give motion to the carriage, substantially as specified. 95

7. The combination, with a standard having a projecting grooved arm mounted thereon, of a starter adapted to slide in said groove and connected to a suitable operating cord and handle, and a carriage adapted to be received by said arm, substantially as specified. 100

8. In a cash-carrier, a hollow standard or support having an elongated slot to receive the cable thereof, and provided with a collar having an aperture adapted to register with said slot, whereby the cable may be adjusted to different elevations in said standard, substantially as specified. 110

9. In a cash-carrier, a hollow standard slotted and provided with internal clamping-jaws and means for clamping said jaws, in combination with a cable adapted to pass within and through the slot in the standard, substantially as specified. 115

10. In a cash-carrier, and in combination with a supporting-standard, the wedge-shaped arm D, slotted, as at I², and provided with the rollers I I', the starter K, and cord L, arranged to pass over said rollers, substantially as specified. 125

11. In combination with the cable B, the cord L, the arm D, and the starter K, provided with the plate K', adapted to embrace said cable, substantially as specified. 130

12. The combination, with a cable and a

- car mounted for travel thereon, of a muffler attached to the car and having continuous contact with the cable during the entire travel of the car thereon, substantially as specified.
- 5 13. In combination with a wedge-shaped receiving-arm, a carriage provided with depending brackets, as G, at its ends, and having rollers G' mounted therein, adapted to em-

brace said arm, and to be stopped thereby, substantially as specified.

In testimony whereof I affix my signature in presence of two witnesses.

DAVID LIPPY.
